UNITED STATES PATENT OFFICE.

CHARLES SPIRO, OF NEW YORK, N. Y.

TYPE-BAR ACTION.

1,072,784.

Specification of Letters Patent.

Patented Sept. 9, 1913.

Application filed February 12, 1913. Serial No. 748,030.

To all whom it may concern:

Be it known that I, CHARLES SPIRO, a citizen of the United States, residing at New York, in the county of New York and State 5 of New York, have invented certain new and useful Improvements in Type-Bar Actions, of which the following is a specification.

This invention relates to a typebar action 10 and particularly to the leverage system thereof.

The invention has for an object to provide a novel and improved construction and arrangement of sub-lever and rocker disposed intermediate of and connected to the typebar and key-lever whereby the leverage upon the sub-lever decreases during the travel of the typebar toward the printing point, thus producing an accelerated movement at the beginning of the stroke and a subsequent steady travel under decreasing leverage as the typebar reaches a substantially vertical position.

Another object of the invention is to provide an improved rocker connection for the sub-lever adjustably mounted on the key-lever so that the degree of acceleration may be regulated and the key lever adjusted to bring the keys into a proper aligned plane at 30 the key board of the typewriter.

Other and further objects and advantages of the invention will be hereinafter set forth and the novel features thereof defined by the appended claims.

35 In the drawing—Figure 1 is an elevation of the typebar action at rest; Fig. 2 is a similar view with the typebar at the printing point, and Fig. 3 a detail of the adjustable connection between the rocker and key lever.

Like numerals of reference refer to like parts in the several figures of the drawing.

The invention is here illustrated as applied to a front strike typewriter, but may 45 be adapted for use with any character of typewriting machine desired.

The typebar 10 is of any usual construction and is pivoted in an ordinary bracket 11 carried by a suitable support 12. An 50 angular sub-lever 13 is pivoted in the

bracket 14 carried by the fixed support 15. The end 16 of the sub-lever is connected with the angle arm 17 of the typebar by a wire or link 18. The end 19 of the sub-lever is formed with an inwardly extending slot or way 20 in which a stud or pin 21 carried by the rocker 22 is disposed. This rocker is normally fixed to the key-lever 23 at an angle to the length thereof, but is also adapted to be adjusted upon said key lever 60 to regulate the acceleration of the typebar movement and the alinement of the key-levers. This adjustment is effected by the slot 24 at the lower end of the rocker through which the fastening screw 25 passes 65 and is mounted in the key lever. The right angle position of the rocker is maintained during adjustment by the steady pin 26 carried by the key lever and extending into the slot 24. The key-lever is pivoted in the 70 usual manner at 27 and provided with the key 28 disposed at the keyboard of the typewriter.

In the operation of the invention a depression of the key lever from the position 75 shown in Fig. 1 to that shown in Fig. 2 carries the typebar to the printing point and during this movement the stud upon the rocker is traveling inward through the slot in the sub-lever thus gradually reducing the amount of leverage exerted thereon. The preliminary draft of the rocker upon the sub-lever is at the point of greatest leverage and produces an accelerated travel of the typebar in leaving its position of rest. This 80 effects an easy start with a light touch at the key-lever and a continued steady movement of the typebar necessary to secure a clear and even impression at the printing point. The rocker when adjusted is rigidly 85 held by the fastening screw and steady pin. By this means any desired degree of acceleration may be secured by shortening or lengthening the rocker and making the sub-lever slotted extension more or less horizontal as desired.

Difficulty has been experienced in leveling up the key board with the usual rigid connection extending from the key lever and this is obviated by the adjustable rocker con- 100

nection which permits the key-levers and keys to be adjusted so that they will lie in a proper alined plane as determined. The steady pin at the adjustable connection always retains the rocker at the proper angle to the key-lever.

This invention is not limited to the specific details of construction herein shown and described, but changes therein may be made without departing from the spirit of the invention.

A single set of operative elements has been illustrated and when the invention is applied to a complete series of elements mounted upon the usual typebar segment variations in the construction of the parts may be required to secure the objects and advantages of this invention.

Having described my invention and set forth its merits what I claim and desire to secure by Letters Patent is—

1. In a typebar action, a typebar, a sub-lever, a connection between said typebar and sub-lever, a key-lever, and a connection from said key lever engaging said sub-lever and mounted to traverse an arc opposite to the arc traversed by the connected end of the sub-lever and adapted to travel toward the pivot of the latter throughout the movement of the typebar toward the printing point.

2. In a typebar action, a typebar, a sub-lever, a connection between said typebar and sub-lever, a key lever, and a connection from said key lever engaging said sub-lever and mounted to traverse an arc opposite to the arc traversed by the connected end of the sub-lever, said arcs being in closest relation when the typebar is at the printing point.

3. In a typebar action, a typebar, a sub-lever, a connection between said typebar and sub-lever, a key lever, and a connection from said key lever engaging said sub-lever and mounted to traverse an arc opposite to the arc traversed by the connected end of the sub-lever, said arcs continuously approaching each other throughout the movement of the typebar toward the printing point.

4. In a typebar action, a typebar, a sub-lever, a connection between said typebar and sub-lever, a key-lever, a connection between said key-lever and sub-lever adapted to produce an initial accelerated movement of said typebar and a subsequent travel under pressure to the printing point, and means for regulating the degree of such acceleration.

5. In a typebar action, a typebar, a sub-lever, a connection between said typebar and sub-lever, a key-lever, and a fixed rocker extending at an angle therefrom and having a movable connection with said sub-

lever arranged to travel toward the pivot 65 of the latter during the movement of the typebar toward the printing point.

6. In a typebar action, a typebar, a sub-lever, a connection between said typebar and sub-lever, a key lever, a fixed rocker 70 extending at an angle therefrom and having a movable connection with said sub-lever, and means for adjusting said rocker relative to said key-lever.

7. In a typebar action, a typebar, a sub-lever, a connection between said typebar and sub-lever, a key-lever, a rocker connected to said sub-lever, and means for adjusting said key-lever in a vertical plane upon said rocker.

8. In a typebar action, a typebar, an angular sub-lever connected therewith and having a slotted arm, a key-lever, and a rocker mounted thereon and having a member disposed in the slot of said arm.

9. In a typebar action, a typebar, an angular sub-lever connected therewith and having a slotted arm, a key-lever, and a rocker adjustably mounted thereon and having a lateral projection disposed in the slot 90 of said arm.

10. In a typebar action, a typebar, an angular sub-lever connected therewith, a key-lever, a fixed rocker mounted thereon at an angle thereto, and a sliding connection between said rocker and sub-lever.

11. In a typebar action, a typebar, an angular sub-lever connected therewith, a key-lever, a rocker mounted thereon at an angle thereto, a sliding connection between said 100 rocker and sub-lever, and a sliding connection between said rocker and key-lever to permit vertical adjustment thereon.

12. In a typebar action, a typebar, an angular sub-lever connected therewith and 105 having a slotted depending arm, a key-lever, and an angularly disposed rocker mounted thereon and having a stud disposed within said slotted arm.

13. In a typebar action, a typebar, an angular sub-lever connected therewith and having a slotted arm, a key-lever, a rocker connected to said arm and provided with a slot at its lower portion, and fastening means carried by the key-lever and extending through said slot.

14. In a typebar action, a typebar, an angular sub-lever connected therewith and having a slotted arm, a key-lever, a rocker connected to said arm and provided with a slot at its lower portion, fastening means carried by the key-lever and extending through said slot, and a steady pin mounted upon the key-lever and disposed within said slot.

15. In a typebar action, a typebar, an operating lever connected thereto, a key lever, and an angularly disposed connection from

said key lever engaging at its free end said operating lever and mounted to traverse an arc opposite to the arc traversed by the connected end of the operating lever and 5 to travel toward the pivot of the latter throughout the movement of the typebar toward the printing point.

In testimony whereof I affix my signature in presence of two witnesses.

CHARLES SPIRO.
